Primary Examiner — Ryan P Harvey

(74) Attorney, Agent, or Firm — McAndrews Held & Malloy, Ltd.

(57) **CLAIM**

The ornamental design for a GAMING MACHINE, as shown and described.

DESCRIPTION

FIG. 1 is a front perspective view of a GAMING MACHINE showing our new design according to a first embodiment;

FIG. 2 is a front elevation view thereof;

FIG. 3 is a right side elevation view thereof;

FIG. 4 is a left side elevation view thereof;

FIG. 5 is a top plan view thereof;

FIG. 6 is a front perspective view of a GAMING MACHINE showing our new design according to a second embodiment;

FIG. 7 is a front elevation view thereof;

FIG. 8 is a right side elevation view thereof;

FIG. 9 is a left side elevation view thereof; and

FIG. 10 is a top plan view thereof.

The dashed broken lines in the figures illustrate portions of the GAMING MACHINE that form no part of the claimed design.

1 Claim, 10 Drawing Sheets(56)
